Primary Examiner — Ruth McInroy(74) *Attorney, Agent, or Firm* — Cantor Colburn LLP(57) **CLAIM**

The ornamental design for an intake for cleaner, as shown and described.

DESCRIPTION

FIG. 1 is a front perspective view of an intake for cleaner, showing our new design;

FIG. 2 is a front view thereof;

FIG. 3 is a rear view thereof;

FIG. 4 is a side view thereof;

FIG. 5 is another side view thereof; and,

FIG. 6 is a top view thereof.

The broken lines illustrating portions of the intake for cleaner form no part of the claimed design.
